UNITED STATES PATENT OFFICE.

ANATOLE BENOÎT, JULIEN GUÉNIFFET, JULES NICHAULT, AND ETIENNE DANGER, OF PARIS, FRANCE.

CIGARETTE-MAKING MACHINE.

No. 800,537.

Specification of Letters Patent.

Patented Sept. 26, 1905.

Application filed January 18, 1905. Serial No. 241,557.

To all whom it may concern:

Be it known that we, ANATOLE BENOÎT, JULIEN GUÉNIFFET, JULES NICHAULT, and ETIENNE DANGER, mechanical engineers, citizens of the Republic of France, residing at 7 Rue Deparcieux, Paris, in the Republic of France, have invented certain new and useful Improvements in Cigarette-Making Machines, of which the following is a specification.

The object of the present invention is a cigarette-machine of large production in which a core or cord of tobacco is formed and fed along continuously, while the paper tubes are carried by a drum moved intermittently along and round its axis. Each tube successively is moved backward and comes in a direction contrary to that of the core of tobacco over the end of the latter. Then immediately it is filled with tobacco it is moved forward. During this latter movement the core of tobacco is cut without being stopped by a blade moved at the same speed of translation as the core itself. As soon as the cut is completed the drum is turned so as to present a fresh paper tube in front of the cut end of the core of tobacco, which paper tube is immediately moved backward to be filled by this core. The large production of the machine results from this mode of general working and from the employment of a special arrangement by which the drum receives a very rapid intermittent rotatory motion. In fact, the filling of the paper tube is accelerated by the fact that the tube and the core of tobacco move in opposite directions. On the other hand, the cutting across of the tobacco is effected without interrupting the forward movement of the latter. Finally, by reason of the arrangement which assures the rapid intermittent rotation of the drum the speed of the continuous movement of the tobacco may be relatively very great without the machine ceasing to work regularly.

The annexed drawings show by way of example a form of execution of the object of the invention.

Figures 1 and 1^a are vertical sections of the entire machine. Figs. 2 and 3 show a plan and elevation of the wheels for feeding forward the tobacco. Fig. 4 is a side elevation of a drum. Fig. 5 shows in vertical section, to a larger scale, some details of feeding-

tubes, of a knife, and of the drum. Fig. 6 is an elevation of mechanism for driving the drum. Fig. 7 is a section taken on line A A of Fig. 6. Fig. 8 is a plan of the same mechanism. Fig. 9 is an elevation of a part of the same mechanism. Fig. 10 is a front elevation of the drum. Fig. 11 is a plan of a pinee.

For the sake of clearness in the description we will designate the back of the machine that part placed to the left of Fig. 1 and the front that part placed to the right, the various movements of the mechanisms being related to the direction of movement of the tobacco indicated by an arrow in Fig. 1.

The general action of the machine is as follows: A transporting-apron *a* on which the tobacco is placed carries the latter between wheels *b*, which compress it and feed it forward in the shape of a continuous core or cord through a funnel *c*. In front of this latter is placed a drum *d*, rotated intermittently by the action of special mechanism *e*, placed at the front of the machine. The compartments in this drum are filled with paper tubes *f* when they pass in front of the mechanism *g* for forming the tubes. Each tube is thus carried in front of the funnel *c* in order to be filled with tobacco. At this point there is also a knife *h*, which cuts the core of tobacco a little behind the paper tube. The cigarette is then carried by the drum successively opposite to a ramming-rod *i*, Fig. 4, which rams the tobacco into the paper tube exactly flush with rear edge of the latter and opposite to an ejector-rod *j*, which pushes the finished cigarette toward the front. The cigarette falls freely out of the drum at *k*, Fig. 6.

The essential parts of the machine will now be described more in detail.

The endless apron is guided over cylindrical rollers 1 and has a continuous motion of translation imparted to it by means of driving-gear. (Not shown in the drawings.) Above the flat and horizontal part of the apron are arranged the wheels *b*, Figs. 2 and 3, comprising a vertical cylindrical wheel 3, two lateral horizontal wheels 4, the surface of which has an upper cylindrical part and a lower part of concave shape, a vertical grooved wheel 5, and two lateral horizontal grooved wheels 6. These wheels are rotated

continuously by gear-wheels 7, so that they all tend to feed forward the tobacco passing between them and the apron. In the space between the wheels 4 and 6 are placed guides 8, which embrace the wheel 5 and the wings of which extend into contact with the wheels 4 and 6, Fig. 2. These guides are supposed to be removed in Figs. 1 and 3. The surface of the wheels 3 to 6 is furnished with oblique flutes or striæ which serve to feed the tobacco forcibly forward. The object of the inclination of the flutes or striæ is to prevent fibers of tobacco being pulled out from the core of tobacco at the place where the wheels 4 and 6 are scraped by the rear points of the guides 8 and the funnel *c* in this sense that these points may fit the wheels exactly without danger of shocks or of wedgings. The successive action of the various wheels 3 to 6 in combination with that of the apron has for effect the regular formation of the core of tobacco and the feeding of it forcibly forward without compressing it more at some parts of its length than at others.

The funnel *c*, Fig. 5, is a tube fixed to an immovable support 9. On the front end of this tube is mounted so that it can slide another tube 10, fixed to a plate 11, having a to-and-fro motion imparted to it. This telescopic prolongation of the funnel *c* is intended to support the core of tobacco always in immediate proximity to the drum *d*, notwithstanding the to-and-fro movement of the latter. The plate 11 and the drum *d* slide together on a shaft 12, the plate being mounted loosely on the boss 13 of the drum between the body of the drum and a loose collar 14, which is held by a ring 15, fixed to this boss. Nevertheless the plate 11 does not follow the rotatory movement of the drum. It is prevented from turning by the spindle 16, fixed to it, and guided in fixed sheaths 17, forming part of the frame, while the drum *d* is driven with the shaft 12 by means of spindles 18, on which it can slide, these spindles being secured to a support 19, rigidly fixed on the shaft.

A to-and-fro movement is imparted to the plate 11 and to the drum *d* by an oscillating lever 20, connected to the collar 14 and operated by a cam 21. This latter is so constructed that in the first part of the forward movement of the drum (period of cutting) the speed of translation of the latter is equal to that of the core of tobacco and that it is a little superior to the same during the last part of the forward movement of the drum, (period of rotation.)

The drum *d* is furnished with a disk 22, carrying a circular row of tubes 23, cut like a whistle, intended to be placed successively in front of the telescopic funnel 10 *c*. The drum also carries a crown 24, in which are formed grooves 25 opposite the tubes 23. Finally,

the drum is surrounded for about three-quarters of its circumference by a guideway or guard 26, which is fixed by cross-pieces 27 to the plate 11, so that it follows the drum in its to-and-fro movements, but without turning with it. This guideway 26 serves to keep the paper tubes in the grooves of the drum. It serves also to support the shaft 28 of the knife *h* and to move it in its to-and-fro movement by means of wings 29. The mechanism, producing the rotatory movement of the drum, is shown in detail in Figs. 6 to 9. On the shaft 12 of the drum are fixed a driving-wheel 30 and a stop-wheel 31, which when required may be made as a single wheel, and are furnished with prismatic notches on their periphery. A lever 32 is mounted loose on the same shaft and is connected by one of its ends to a sliding rod 33, guided on a continuously-rotating driving-shaft 34. This rod carries a roller 35, which takes into an eccentric groove 36 of a plate 37, fixed to the shaft 34, so that the rotation of the latter imparts a to-and-fro movement to the rod 33 and lever 32. The other end of the lever 32 is furnished with a radially-directed slide-guide 38 and in which moves a slide 39, carrying a tooth 40, intended to engage between the teeth of the wheel 30. This slide receives a to-and-fro motion by means of a grooved cam 41, acting upon a roller 42, placed on the slide. The said cam turns freely on the shaft 12 and has imparted to it a continuous rotatory motion by gear-wheels 43, which are propelled by a motor-driven shaft 34, so that at each rotation of the driving-shaft 34 the cam 41 causes the tooth 40 to engage with the wheel 30 during a fraction of the revolution and causes it to disengage therefrom during the rest of the revolution. The arrangement comprises also a stop-lever 44, oscillating on a fixed axis 45 and operated at one end by a cam 46, fixed to the shaft 34, and at the opposite end by a spring 47. On one end of this lever is fixed a tooth 48, opposite to the wheel 31, so that at each revolution of the shaft 34 the tooth 48 is engaged with the wheel during a fraction of the revolution and disengaged therefrom during the rest of the revolution. The movements of the slide 39 and of the levers 32 and 33 are so coördinated that the tooth 48 is disengaged from the wheel 31 after the tooth 40 is engaged with the wheel 30 and before the lever 32 oscillates in the forward direction indicated by an arrow in Fig. 6, and that afterward the tooth 48 engages with the wheel 31 after the lever 32 has stopped and before the tooth 40 is disengaged from the wheel 30. The return movement of the lever 32 commences after the tooth 40 is disengaged and ends before this tooth engages afresh with the wheel 30. The result is that the system of wheels 30 31 is

never left to itself and that its connections with the machine prevent its becoming deranged or acting irregularly, whatever may be the frequency and rapidity of the intermittent advance movements. At each revolution of the shaft 34 the drum *d* is thus turned through an angle corresponding to the distance apart of two consecutive grooves 25.

The knife *h* has a continuous rotatory movement imparted to it and is arranged to pass into the narrow space between the plate 11 and the disk 22, of which it follows at the same time the to-and-fro longitudinal movement. The knife is fixed on the shaft 28, which is driven by power, so as to cut the core of tobacco during the forward movement of the drum, and consequently accompanies the tobacco in its continuous movement of translation.

On the guideway 26 are also arranged two pincers 49 and 50, each of which consists of an india-rubber roller mounted so as to turn on a spring 51, fixed to the guideway, Figs. 10 and 11. Each of these rollers rests elastically upon two of the tubes 23, which pass successively beneath them, and their object is to hold the paper tubes *f* on the tubes 23 from the filling operation to that of ejection.

The ramming and ejecting spindles *i* and *j*, Figs. 4 and 10, are fixed to a sliding piece 52, which has a to-and-fro movement imparted to it by means of the rod shown immediately to its left in Fig. 4. They are of such lengths that the front end of the spindle *i* passes into the tubes 23 of the drum until flush with the front face of the disk 22, while the end of the spindle *j* advances beyond the point of the said tubes. The spindle *i* serves to push into each cigarette the little plug of tobacco resting in the thickness of the disk 22 after the cut. The spindle *j* serves to disengage the cigarettes from the tubes 23, so that they can fall freely when they arrive at *k* at the end of the guideway 26.

The mechanism for making the paper tubes is well known. It is sufficient to say here that the continuous tube formed on the spindle 53 by pasting or by hooking one edge of the strip of paper into the other edge is cut by the scissors 54, having a to-and-fro movement imparted to them in such manner that at the moment when the drum *d* does not turn and is moved forward the scissors 54 push the paper tube they have just cut off into the groove 25 and onto the corresponding tube 23.

One can now sum up the general action of the machine. The tobacco placed onto the apron *a* is formed into a core or cord and is fed forward forcibly by the wheels 3 to 6 through the telescopic funnel *c*, 10, whence it issues with a continuous movement of translation. On the other hand, each paper tube *f* pushed by the scissors 54 onto the tube 23 is brought to the interior of the guideway 26

by intermittencies and participating in the to-and-fro movements of the drum *d* until opposite the funnel *c* and is then held by the pincer 49. Immediately the paper tube has arrived opposite the funnel it is pushed backward, so as to surround the core of tobacco which issues from the funnel. As soon as the filling is completed the paper tube is returned forward. During this movement the knife first cuts off the tobacco between the disk 22 and the front end of the tube 10, which does not cease to support the roll. Then the partial rotation of the drum takes place. A fresh paper tube is brought in front of the core of tobacco, is pushed onto it, and so on. The tube filled with tobacco is still held by the pincer 49, then by the pincer 50, while the rod *i* rams the tobacco flush with the rear edge of the paper tube. The paper tube released by the pincer 50 is afterward disengaged from the tube 23 and the finished cigarette finally falls out at *k*.

We claim—

1. A cigarette-machine comprising an endless apron and wheels for feeding forward a core or cord of tobacco, a drum adapted to carry paper tubes, means for placing the paper tubes on the core of tobacco and means for cutting the core of tobacco at the entrance of each tube, means for imparting a continuous movement to the endless apron and to the wheels for feeding forward the core of tobacco, and means for causing the drum to advance and recede in relation to the said wheels.

2. A cigarette-machine comprising means for feeding forward a core of tobacco continuously, a tube-carrying drum adapted to slide and rotate, means for moving the drum forward and backward in relation to the core of tobacco, and means for turning the drum at the moment when it is farthest removed in relation to the core of tobacco.

3. A cigarette-machine comprising means for feeding forward continuously a core of tobacco, a tube-carrying drum adapted to slide and rotate, means for moving the drum forward and backward in relation to the core of tobacco, a knife adapted to cut the core of tobacco, this knife being arranged to move to and fro with the drum, means for actuating this knife while the drum is moving in the same direction as the core of tobacco and means for causing the drum to turn at the moment when it is farthest removed in relation to the core of tobacco.

4. In a cigarette-machine the combination of a rotating drum, a series of tubes 23 on this drum adapted to receive around them one end of the paper tubes, and a roller mounted on a fixed but elastic support in such manner that this roller presses successively on the said tubes to hold the paper tubes on them.

5. In a cigarette-machine the combination

of two pairs of horizontal wheels, a vertical wheel placed in front of the first pair of horizontal wheels and a vertical wheel placed between the two pairs of horizontal wheels, the 5 first vertical wheel having a straight profile the first horizontal wheels having a curved profile outside below, and the last vertical and horizontal wheels having a semicircular concave profile, and a belt for actuating said 10 wheels.

6. In a cigarette-machine the combination of a fixed tube *c* for the outlet of the core of tobacco a sliding and rotating tube-carrying drum a plate which slides with the drum 15 without turning, and a tube 10 on this plate, this tube sliding on the fixed tube *c*.

7. In a cigarette-machine the combination of a shaft, a sliding drum, a plate loose on the boss of the drum, means for forcing the plate 20 to follow the to-and-fro movement of the drum, spindles 18 on the shaft engaging the drum for forcing it to turn, spindles 16 on the plate engaging with the frame for preventing the plate from turning, a guideway or guard 25 26 fixed to the plate and partially surrounding the drum, a shaft on this guideway or guard and a rotating knife on this shaft, this knife being adapted to pass between the said plate and the drum, and the plate being furnished with a mouthpiece 10 for the passage 30 of a core of tobacco.

8. In a cigarette-making machine, the combination of an endless apron, mechanism for actuating the same so as to feed a core of tobacco continuously, a drum disposed adjacent to said apron and provided with grooves for holding paper tubes, mechanism for placing said paper tubes upon said core of tobacco, mechanism for cutting said core of tobacco 35 at a point adjacent to the ends of said tubes, and means for ejecting the finished cigarette from said drum.

9. The combination of means for feeding a core of tobacco continuously, a drum provided with means for holding a plurality of paper tubes, mechanism for reciprocating said drum in a direction parallel to the direction of movement of said core of tobacco, and cutting mechanism adapted to move bodily 40 45 50 with said drum for the purpose of periodically severing said core of tobacco.

10. In a cigarette-making machine, the combination of means for feeding a core of tobacco continuously, a slidably-mounted 55 drum adapted to rotate, driving mechanism for sliding said drum in a general parallel direction with its axis and also for rotating the same upon its axis, said drum being provided with means for holding paper tubes and for 60 causing the same to register successively with said core of tobacco, cutting mechanism for periodically severing said core of tobacco, and means for ejecting the finished cigarette from said drum.

11. In a cigarette-making machine, the 65 combination of means for feeding forwardly continuously a core of tobacco, a tube-carrying drum adapted to slide in the direction of its axis and to rotate upon said axis, said drum being provided with means for holding paper tubes, mechanism for rotating said drum so as to bring said paper tubes successively into registry with said core, mechanism for moving said drum bodily back and forth in the general direction of the length of 70 said tobacco core, and mechanism movable bodily with said drum for periodically severing said core of tobacco.

12. In a cigarette-making machine, the combination of mechanism for feeding forwardly 80 continuously a core of tobacco, a tube-carrying drum adapted to slide in the general direction of the length of said core and to rotate upon an axis parallel with said core, means for moving said drum backward 85 and forward and also for causing it to rotate, a knife adapted to cut said core of tobacco periodically, and means for causing said knife to move bodily in accordance with the to-and-fro movements of said drum. 90

13. In a cigarette-making machine, the combination of a revoluble drum provided with means for holding a series of paper tubes, means for rotating said drum step by step so as to bring said tubes successively 95 into registry with a certain point, mechanism for feeding a roll of tobacco continuously toward said point, means for causing said drum to move axially in the general direction of the length of said core so as to force 100 said tubes successively over said core, and cutting mechanism movable bodily with said drum for the purpose of periodically severing said core of tobacco.

14. In a cigarette-making machine, the 105 combination of a rotating drum, a series of metallic tubes mounted thereupon and adapted to receive paper tubes, and a roller for successively engaging said metallic tubes so as to hold the paper tubes thereon. 110

15. In a cigarette-making machine, the combination of a plurality of wheels arranged in pairs, a vertical wheel placed in front of the first pair of wheels, a vertical wheel placed between two successive pairs of 115 wheels, said first vertical wheel having a straight profile, the pair of wheels adjacent thereto having curved profiles, and the other wheels having concave profiles, all of said wheels being for the purpose of feeding a roll of tobacco, a belt for actuating said wheels and mechanism for placing tubes upon said roll of tobacco and for cutting the same into lengths suitable for cigarettes. 120

16. In a cigarette-machine, the combination of a drum, means for imparting thereto a rapid intermittent rotary motion, said drum being provided with means for tempo-

rarily holding paper tubes, means for feeding a core of tobacco continuously toward said drum, mechanism for actuating said drum in the general direction of the travel of said core of tobacco, cutting mechanism for severing said core periodically, and plunger mechanism for compressing within the paper tubes the portion of tobacco thus cut off.

5 In testimony that we claim the foregoing

as our invention we have signed our names 10
